UNITED STATES PATENT OFFICE.

CHARLES E. DELANO, OF VALLONIA, INDIANA.

COTTON CHOPPER AND CULTIVATOR.

SPECIFICATION forming part of Letters Patent No. 723,444, dated March 24, 1903.

Application filed January 6, 1902. Serial No. 88,680. (No model.)

To all whom it may concern:

Be it known that I, CHARLES E. DELANO, residing at Vallonia, in the county of Jackson and State of Indiana, have invented certain new and useful Improvements in Cotton Choppers and Cultivators, of which the following is a specification.

My invention relates to devices for thinning cotton-plants, and has for one of its objects to provide a device that is at all times under the control of the operator.

Another object of my invention is to provide a device that has two wheels with slantingly-disposed rims, each wheel carrying a series of lever-operated and spring-returned cutting-blades, pairs of said blades on the two wheels swinging toward each other simultaneously and forming an equivalent to a pair of shears.

Another object of my invention is to provide means for actuating the above-described cutting-blades or preventing their operation, as the nature of the work and the judgment of the operator may dictate.

Another object is to so construct the running-gear and connect it with the wheels carrying the cutters that said cutter-wheels may at all times straddle the row, notwithstanding the direction given to the machine by the draft-animals. This is a very important consideration, because the rows are not always exactly straight, and the complete operation of the machine is at all times assured without the need of worrying the animals by having to make them follow the row.

A further object of my invention is to provide vertically-adjustable cultivator-blades to follow the chopper, which may be raised and lowered at the will of the operator.

I attain these objects by the mechanism illustrated in the accompanying drawings, in which—

Figure 1 is a side view in elevation of my invention; Fig. 2, a top plan view; Fig. 3, a detached view in elevation of the wheels carrying the cutting-blades and the frame in which they are journaled; Fig. 4, a top plan view of the device with the chopping-wheels and frame removed; Fig. 5, a detail view of one of the brackets and swivel-bars; Fig. 6, a detail view of a pair of cutting-blades; Fig. 7, a view of one of the rods carrying the cut-

ting-blades, and Fig. 8 a detail view of lever for operating cultivator-beams.

In the drawings, in which similar reference characters indicate corresponding parts throughout the several views, 1 represents the frame of my machine, made, preferably, of a rectangular form and has the draft-pole 2 secured to one end of the frame and braced by bars 3.

4 represents the operator's seat, which is of any desired form and supported by the goose-neck 5 to the rear end of the frame 1. Midway of each side of the frame 1 are secured the brackets 6, in the arms of which are journaled the rectangular swivel-bar 7.

8 represents the driving-wheels, which are journaled on the arms 9, secured to said rectangular swivel-bar 7.

10 represents a frame pivotally secured to the rod 11, which is secured through the sides of the frame 1, just back of the front end of said frame, said frame 10 having near its front and rear ends curved flat bars 10^a and 10^b, respectively, which are segments of the same circle.

12 represents another frame narrower than the frame 10 and having its front and rear ends 12^a and 12^b curved in the same degree and direction as the parts 10^a and 10^b.

13 represents a downwardly-dependant bracket from each side of the frame 12, which supports the axle 14, on which is journaled the hollow shaft 14^a, and secured near each end of said hollow shaft 14^a is a wheel 15, having a slanting rim 16.

17 represents a circular metal band mounted by means of the angular brackets 17^a to the spokes of each wheel 15, said band being concentric with said rim 16 of said wheel 15.

18 represents rods journaled in the rim 16 and brackets 19, mounted on said band 17, having their free ends bent at right angles, as shown at 18^a.

20 represents a cutting-blade secured to each rod 18 near the inner side of the rim 16 of the wheel 15 and has a cutting edge 20^a. The cutting-blades on the two wheels are arranged opposite each other, and when in operation, as hereinafter described, swing across the median line between the wheels 15, and consequently are an equivalent to a pair of shears.

21 represents a lever having the handle portion 21^a and the two parallel arms 22 each fulcrumed in the bracket 13 on each side of the frame 12. The free end of each arm 22 is bent, as shown at 22^a, and is adapted to successively actuate the cutting-blades 20 by tripping the rod 18 and causing it to turn when the lever is properly adjusted by the operator, so that the ends 22^a of the arms 22 intercept the bent ends 18^a.

18^b represents a coil-spring wound around each rod 18 and connected thereto at its lower end, while at its upper end it is secured to the band 17. The purpose of the coil-springs 18^b is to return the cutting-blades 20 to their normally open position, when the bent portions 18^a are released by the ends 22^a of the arms 22 by twisting the rod 18 back to its normal position.

20 The frame 12 and the parts connected therewith rest upon the frame 10, the segmental portions 12^a and 12^b being mounted upon the segmental portions 10^a and 10^b, respectively, and are adapted to swing thereon. The segmental portions 10^a and 12^a and 10^b and 12^b, respectively, are held together by means of the clamps 23, secured to said front and rear ends 10^a and 10^b and bent over the top of the front and rear ends 12^a and 12^b.

25 24 represents rods pivotally secured in their centers to the rectangular swivel-bar 7 and connected to the center of the segmental ends 12^a and 12^b by means of hooks 25, secured to pins 26 in the center of said ends 12^a and 12^b. It will now be understood that the driving-wheels 8 and the cutting-wheels 15 swing together, so that the four wheels are always parallel. This swinging is controlled by the operator, who places one foot on each

30 pedal 27, connected, by means of the curved bar 27^a, to the swivel-bar 7. It will also be understood that by pivoting the frame 10 to the front of the machine, as above described, sufficient up-and-down play is permitted the 35 cutter-wheels 15 to permit them to adapt themselves to the inequalities of the ground, means being provided, as will be hereinafter described, to prevent the wheels 15 jumping upward too far, as might possibly be the case 40 if a large stone or other obstruction be encountered.

28 represents beams pivoted to the rod 11 on each side of the cutter-wheels 15, each having its rear end bent toward the other

45 55 back of the wheels 15, as shown at 28^a, and having mounted thereon a disk cultivator-blade 29. The beams 28 are raised and lowered by means of the bell-crank levers 30, fulcrumed to each side of the frame 1, as shown 60 at 30^a, and connected to each beam 28 by means of the link 31, pivoted to said beam and the end of said lever 30.

50 65 32 represents a lever for operating the bell-crank levers 30, which is fixed to one end of the rod 33, journaled in the sides of the frame 1, near the rear end thereof, and 34 an arm secured to the opposite end of the rod 33.

The lever 32 and arm 34 have each a rod 35 pivoted thereto and having a reduced and rounded end 35^a, that fits into an eye 30^b in 70 the upper end of the bell-crank lever 30 on that side of the machine.

36 represents a coil-spring wrapped around each rod 35 and secured to the bell-crank lever. The purposes of this construction of 75 rod and spring are threefold—first, the tension of the spring assists in lowering the beam when the lever 32 is thrown back; second, the tension of the spring serves to give the cultivator-blades an operation similar to 80 a spring-cultivator, holding the cultivator-blade in the soil except when a hard obstruction is encountered, when the bell-crank lever 30 is moved back on the reduced portion 35^a, passing through the eye 30^b, the spring 85 instantly returning the blade to its normal position when past the obstruction, and, third, the shoulders 35^b, formed by the reduced portion 35^a, push the bell-crank levers back when the lever 32 is thrown forward, 90 thus raising the beams.

37 is an ordinary construction of segmental rack for adjusting the angle of the operating-lever 32 and the consequent height of the disks 29, 37^a representing a stop which is used 95 when the blades 29 are not in operation.

38 represents a bolt slidably mounted in brackets 39 on the side of the lever 32 and held in rack 37 or stop 37^a by means of the coil-spring 40 bearing against the upper 100 bracket 39 and secured to said bolt 38 through a hole therein. The bolt 38 is withdrawn from engagement with said rack or stop 37^a by means of the lever 41, pivoted to the lever 32 near its free end, and the link 41^a, connecting said lever 41 and the head of the bolt 38.

42 represents a chain connecting each beam 28 with the rear of the frame 10, said chains and beams 28 acting as drags to prevent said frame 10 being thrown up too high should 110 the wheels 15 strike an obstruction.

By the construction above described it will be readily seen that the two wheels 15 straddle the row of growing cotton and when the lever 21 is adjusted properly the cutting-blades 20 cut out plants at intervals in the row, while by adjusting the beams 28 the disks 29 throw the soil from each side to the growing plant.

Having thus described my invention, what 120 I claim is—

1. In a cotton-chopper, wheels having chopping-blades attached thereto, driving-wheels parallel with said wheels, and means to simultaneously swing all of said wheels, substantially as shown and described.

2. In a cotton-chopper, wheels having chopping-blades attached thereto, driving-wheels parallel with said wheels, and means to simultaneously swing all of said wheels in parallel 130 planes, substantially as shown and described.

3. In a cotton-chopper, parallel wheels carrying chopping devices, driving-wheels parallel with said wheels, and means to cause all

of said wheels to swing simultaneously, substantially as shown and described.

4. In a cotton-chopper, driving-wheels swivelly mounted, wheels having chopping-blades attached thereto and mounted to swing in a horizontal plane, and means to cause a simultaneous swinging of all of said wheels, substantially as shown and described.

5. In a cotton-chopper, driving-wheels mounted to swing in a horizontal plane, a frame suitably mounted to swing with said driving-wheels and be always parallel therewith, wheels having cutting-blades attached thereto journaled in said frame, and means to cause a simultaneous swinging of said wheels, substantially as shown and described.

6. In a cotton-chopper, two wheels carrying cutting-blades, and means to cause said cutting-blades to simultaneously swing across the median line between said wheels and to return to their normal position, substantially as shown and described.

7. In a cotton-chopper, two wheels carrying cutting-blades, and means to cause said cutting-blades to successively swing in pairs across the median line between said wheels and to return to their normal position, substantially as shown and described.

8. In a cotton-chopper, two wheels having slanting rims, rods journaled on said wheels, cutting-blades mounted on said rods, means to cause said rods to swing on their axes in pairs carrying the cutting edges over the median line between said wheels, and springs to return said cutting-blades to their normal position, substantially as shown and described.

9. In a cotton-chopper, a rectangular frame, the driving-wheels swivelly mounted thereon, a vertically-swinging frame supported in said rectangular frame, a frame supported by said vertically-swinging frame, wheels carrying cutting-blades journaled in said frame, and means to cause a simultaneous swinging of all of said wheels, substantially as shown and described.

10. In a cotton-chopper, a rectangular frame, brackets secured on each side thereof, a driving-wheel swiveled in each bracket, a frame pivoted in said rectangular frame, a frame mounted to swing on said pivoted frame, means to cause a simultaneous swinging of said driving-wheels and swinging frame, wheels journaled in said swinging frame, and cutting-blades mounted in said wheels, substantially as shown and described.

11. In a cotton-chopper, a rectangular frame, beams pivoted to the front thereof having cultivator-blades at the rear, a bell-crank lever pivoted on each side of said rectangular frame and connected to each beam by a link, a lever and arm keyed to a rock-shaft journaled on said rectangular frame, a rod pivoted to each said arm and lever, each rod having a reduced end portion passing through an eye in the end of said bell-crank lever, and a coil-spring connecting each rod with each

bell-crank lever, substantially as shown and described.

12. In a cotton-chopper, a frame mounted to be swung horizontally, two wheels mounted on a common hub and spaced apart journaled in said frame, rods journaled in each wheel having an angular projection thereon, a manually-operated lever having a U-shaped extension to actuate said rods successively in pairs, cutting-blades mounted on said rods, and means to return said rods and cutting-blades to their normal position, substantially as shown and described.

13. In a cotton-chopper, a rectangular frame, a bracket secured on each side thereof, a swivel-bar journaled in each bracket, a driving-wheel journaled on each swivel-bar, a frame pivoted in said rectangular frame, a frame slidably mounted on said pivoted frame and adapted to carry the chopping apparatus, a rod pivotally secured at its center to each swivel-bar, and hooks connecting each end of each rod with the center of the corresponding end of said slidably-mounted frame, substantially as shown and described.

14. In a cotton-chopper, two wheels having slanting rims, a circular plate suitably secured to the spokes of said wheel, a succession of rods journaled in the rim and in brackets secured to said circular plate in each wheel, cutting-blades mounted on each rod near the rim of each wheel, means to cause said cutting-blades to successively swing in pairs across the median line between said wheels and to be returned to their normal position, substantially as shown and described.

15. In a cotton-chopper, a rectangular frame, a bracket secured near the center of each side of said frame, a swivel-bar journaled in each bracket, a driving-wheel journaled on each swivel-bar, a frame pivoted in said rectangular frame, said frame having segmental front and rear ends, a frame adapted to carry the chopping apparatus having segmental front and rear ends adapted to slide on the segmental front and rear ends of said pivoted frame, and means to cause a simultaneous swinging of said driving-wheels and sliding frame, substantially as shown and described.

16. In a cotton-chopper, a rectangular frame, driving-wheels mounted on said frame and adapted to swing in a horizontal plane, a frame pivoted near the front of said rectangular frame having segmental front and rear ends, a frame mounted on said pivoted frame connected to and adapted to swing with said driving-wheels, wheels journaled in said frame and spaced apart, reciprocating cutting-blades journaled in said wheels, and means whereby said cutting-blades are made to operate or to cease operation, substantially as shown and described.

17. In a cotton-chopper, a rectangular frame, a bracket on each side thereof, a swivel-bar journaled in each bracket, a driving-

wheel journaled on each swivel-bar, a frame having segmental front and rear ends pivoted in said rectangular frame, a frame having segmental front and rear ends mounted on said pivoted frame to swing in a horizontal plane, downwardly-extending brackets from each side of said swinging frame, two wheels spaced apart on a common hub journaled in said brackets, rods journaled in said wheels, a cutting-blade secured to each rod, said rods and cutting-blades on each wheel being oppositely disposed, a lever journaled in said downwardly-extending brackets having forked ends adapted to oscillate said cutting-blades,

a coil-spring on each rod to return the cutting-blade to its normal position, means to simultaneously swing said horizontally-swinging frame and driving-wheels, in combination with vertically-swinging plow-beams, and means to adjust them at any desired height, substantially as shown and described.

In testimony whereof I hereto affix my signature in the presence of two witnesses.

CHARLES E. DELANO.
